INCORPORATED, OF WEST ORANGE, NEW JERSEY, A CORPORATION OF NEW JERSEY

TIME SETTING AND TIME CONTROL MECHANISM FOR AUTOMATIC TOASTERS AND
THE LIKE

Application filed November 4, 1929. Serial No. 404,547.

This invention relates to time setting and time control mechanism for automatic toasters and the like and more particularly is an improvement on the apparatus shown and 5 claimed in the copending application of Charles A. Schallis, filed November 4, 1929, Serial No. 404,810, entitled Automatic toaster assigned to Thomas A. Edison, Incorporated, to which reference may be had 10 for a more complete understanding of the associated apparatus with which my invention is intended to function.

Since this invention per se relates to an improvement in the time control and release 15 mechanism only and does not involve other elements such as the latching mechanism and the like, I have shown only the particular apparatus with which my invention is concerned and the apparatus with which it is 20 directly associated.

In a general way however it may be stated that a toaster of the class to which my invention is particularly applicable includes latching mechanism for the purpose of holding 25 the grates in juxtaposition with the article to be heated and also trip mechanism for disengaging the latch at the end of a predetermined time to permit the grates to move away from the article to be heated. The 30 time control mechanism consists of a suitable clockwork which drives a trip in a direction to engage a finger associated with the latch in order to move the latch out of latching position and permit the grates to move 35 away from the toast. For the purpose of controlling the time interval during which the grates remain in juxtaposition with the toast, without varying the position to which the clockwork is wound, the latch trip is 40 provided with a cam face 6 which engages the latch, and the latch trip is so arranged as to be movable in one direction by the energizing clockwork and to be movable in a different direction by the time control mechanism. 45

The features of novelty which I believe to be characteristic of my invention are set forth with particularity in the appended claims: My invention itself, however, both as to its fundamental principles and as to its 50 particular application will best be understood by reference to the specification and the accompanying drawing in which:

Figure 1 is a plan view of apparatus according to my invention. 55

Figure 2 an elevational view partly in section.

Figure 3 is a fragmental plan of the trip lever showing the slot therein.

Figure 4 is a sectional view of the setting 60 lever on line 4-4 of Figure 1 with a diagrammatic view of the co-operating notches and scale.

Referring now more particularly to the drawing, L designates a latch pivoted as at 65 1' upon the pedestal 2' secured to the base 1, the latch being arranged for rotation about the said pivot. In the position shown in Figure 1 the latch is in engaged position in which the grates are held closed. The cam 70 face 6 of the trip lever T is arranged to engage the face of extension L' of the latch and to rotate the latch counter clockwise (as is hereinafter more fully set forth) thereby releasing the grates and permitting 75 them to fall. The latch is biased by spring 6' towards the position shown but the spring bias is not sufficient to maintain the latch in position against the pressure of the cam face which engages the downwardly turned extension L' upon the latch. 80

The trip lever T is pivoted at its opposite end at point 7 upon a driving arm or member 8 which is carried by the clockwork mechanism diagrammatically shown as 9 and energized by spring 10 and may have intermediate depressions forming bearing surfaces against base plate 1, thereby permitting the trip lever bearing the cam face 6 to slide on the base plate. The time control or time 85 90 95

- setting lever 3 is pivoted at its inner end at 2 and has a resilient portion at its outer end provided with a rib 4 and is also provided with an operating button 5. The rib 4 is adapted to engage a series of notches 9' in the cooperating index or scale 10', diametrically shown in Figure 4, by means of which the lever 3 may be set in the angular position desired.
- 10 An intermediate point on the lever 3 is connected to an intermediate point upon the trip lever by means of a link 11 having one end pivoted to the lever 3 and the other end pivoted to the trip lever.
- 15 From this it will be seen that if the lever 8 is held stationary for any reason, movement of the end 5 of lever 3 will cause the cam face 6 of the trip to move substantially upward and downward in Figure 1 whereas on the other hand if the lever 3 is fixed in position, operation of the clockwork mechanism which controls the movement of the lever 8 as it is moved counter clockwise under the influence of spring 10, will cause
- 20 the cam face 6 to move in a substantially straight line across the paper in Figure 1 and at a given point in such movement engage the extension L' of the latch. This permits an easy control of the time required
- 25 for the clockwork to disengage the latch L, since it will be understood that by moving the lever 3 downwardly in Figure 1, the trip lever T with its cam face 6 is moved downwardly and consequently a lesser rotation of arm 8 will serve to trip the latch.
- 30 For the purpose of preventing the latch from being moved too far out of position there is a provided finger 19 which may be struck up from the base plate 1. Under certain conditions movement of the lever 3 might cause the cam face 6 to strike against finger 19 and further pressure applied against the end of lever 3 would merely serve to distort and perhaps permanently injure the mechanism. To prevent such action, I provide a yielding connection interposed between lever 3 and the trip lever. Although this connection may be provided in other ways, I prefer to provide slot 14 in the trip lever and to provide a stud 15 on link 11 which stud 15 engages said slot. For the purpose of normally maintaining the stud 15 in the slot 14 there is provided a spring 16 positioned between studs 15 and 17 on the one hand and stud 18, both of the latter studs being mounted on the trip lever. The arrangement is such that the spring 16 normally exerts a sufficient tension holding the stud 15 in slot 14 to permit of normal adjustment of the time control lever 3. However, should the cam face 6 strike any unyielding obstacle such as finger 19 which would prevent its further movement then the spring 16 will yield and permit the stud 15 to move out of the slot 14. As soon as

the pressure is relieved the action of this spring will cause stud 15 to work back into position in the slot. It will thus be seen that such a connection permits normal adjustment of the time control lever while at the same time eliminating the danger of bending the various levers.

While I have shown and described the preferred embodiments of my invention, it will be understood that modification and changes may be made without departing from the spirit and scope of my invention as will be understood by those skilled in the art. In particular, while I have shown the yielding connection at one point on link 11 it will be understood that the connection may be made on the opposite end or that other changes may be made without departing from the spirit of my invention.

I claim:

1. In apparatus of the class described, in combination, a driving member, a trip lever having at one end a cam face, and pivotally connected at the other end to said driving member, a setting lever pivotally connected at one end for time control movement, and a yielding connection between intermediate points on said setting lever and said trip lever.

2. In apparatus of the class described, in combination, a driving member, a trip lever having at one end a cam face, and pivotally connected at the other end to said driving member, a setting lever pivotally connected at one end for time control movement, and a yielding and resilient connection between intermediate points on said setting lever and said trip lever.

3. In apparatus of the class described, in combination, a driving member, a trip lever having at one end a cam face, and pivotally connected at the other end to said driving member, a setting lever pivotally connected at one end for time control movement, and a link connected at one end to an intermediate point on said setting lever and at the other end to an intermediate point on said trip lever, one of said connections being yielding and resilient.

4. In apparatus of the class described, in combination, a driving member, a trip lever having at one end a cam face, and pivotally connected at the other end to said driving member, a setting lever pivotally connected at one end for time control movement, a link connected at one end to an intermediate point on said setting lever and at the other end to an intermediate point on said trip lever, said link having a pin at one end engaging a slot in one of said levers, and resilient and yielding means for maintaining said pin in said slot.

5. In apparatus of the class described, in combination, a driving member, a trip lever having at one end a cam face, and pivotally

connected at the other end to said driving member, a setting lever pivotally connected at one end for time control movement, a link connected at one end to an intermediate point on said setting lever and at the other end to an intermediate point on said trip lever, said link having a pin at one end, engaging a slot in one of said levers, and resilient and yielding means for maintaining said pin in said slot, said means comprising a spring extending longitudinally of the slotted lever and secured thereto.

This specification signed this 2nd day of Nov. 1929.
